J. GOODIN, Jr.

Sad Iron.

No. 18,543.

Patented Nov. 3, 1857.

UNITED STATES PATENT OFFICE.

JAMES GOODIN, JR., OF CINCINNATI, OHIO.

SMOOTHING-IRON.

Specification of Letters Patent No. 18,543, dated November 3, 1857.

To all whom it may concern:

Be it known that I, JAMES GOODIN, Jr., of the city of Cincinnati, county of Hamilton, and State of Ohio, have invented a new and useful Improvement in Smoothing-Irons; and I do hereby declare that the following is a full and exact description thereof, reference being had to the accompanying drawings and made to form part 10 of this specification and to the letters of reference marked thereon.

Similar letters refer to like parts of the improvement.

The nature of my improvement consists 15 in the arrangement of the different portions together employed for heating the iron by which I am enabled to distribute and retain the heat in the bottom of the iron and keep it sufficient hot during the time of ironing 20 without stopping to heat the iron as is commonly the case with all ordinary methods of heating irons for smoothing purposes with charcoal or gas.

To enable others skilled in the art to make 25 and use my improvement I will proceed to describe its construction and operation by referring direct to the accompanying drawing of which—

Figure 1, represents a longitudinal sectional elevation of the improved iron. Fig. 2, is a horizontal sectional view of the same. Fig. 3, is a perforated diaphragm placed in the iron and employed to help retain the most of the heat in the iron and assist in 35 distributing it over the lower surface of the iron. Fig. 4, is a perspective view of the iron with the top and handle of it removed and furnished with an opened plate for boiling water and similar purposes with the gas 40 if desired.

A is the iron made of an ordinary form and hollow and B, B, is a gas pipe bent and formed to suit the shape of the bottom of the iron around its edges and back part and 45 perforated with openings for the escape of the gas against the sides and end of the iron—for, if the gas was allowed to strike against the bottom of the iron it would smoke and heat in spots where the jet of

50 gas would strike and if allowed to escape from the top of the pipe B, the heat would have a tendency of rushing out of the iron through the chimney. But when made to escape at the side of the pipe B, against the 55 side of the iron the difficulties before stated are more or less obviated by retaining the

heat and cause it more equally to distribute itself over the iron.

The gas is let into the pipe B, B, with a flexible tube connected to the iron at the 60 joint piece d and f.

C, C, is a wire gauze placed around the pipe B, in the iron for distributing the gas evenly over the surface of the iron as much as possible.

g, g, is a perforated plate set in at the 65 top of the iron about one third of the depth of the iron from its top for helping in retaining and distributing the heat over the surface of it by retarding the escape of the 70 heat into the chimney (i).

p is the top of the iron furnished with a handle k and chimney pipe (i) and is held 75 to its place by a rod passing through the lugs J, attached to the iron and its top.

5, 5, 5, and 7, 7, 7, 7, are air openings 80 for supplying the gas with air for combustion and assist in distributing the heat equally over the surface of the iron. The combined use of the air holes 5 and 7, with 85 the plate g, g, serve to equally distribute and retain the heat over the surface of the bottom of the iron by the following action of the air and use of the plate: When gas is admitted to the inside of the iron and 90 ignited by air passing in the openings 5, 5, if it was not for the air openings 7, 7, on 95 each side of the iron the heat of the gas and flame would have a tendency of rushing to the chimney and pass off without heating the iron but with the use of the air openings 7, 7, air is admitted to the top of the flame which retains and distributes it and the heat—with the help of the plate g, g, over the surface of the bottom of the iron, 95 and thus by the arrangement of the air openings 5, and 7, and plate g, g, with the 100 gas apparatus B in the bottom of the iron the heat is retained and distributed evenly over the bottom of the iron—sufficient at all times to keep it hot enough to iron with without being necessary for the operator to stop work for the iron to heat, as is commonly the case when irons have been heated with charcoal or gas.

10, 10, Fig. 4, is a plate placed on the top of the iron when the handle is removed, and furnished with an opening 8, for placing a vessel of water on to be heated by the gas and 9 is another opening in the plate to 110 give a draft, and when the gas in the iron is being used for heating water and similar

purposes the plate g, g , in the iron will be removed in such cases so as to give the heat a better chance to act on the vessel containing the water.

5 I am aware of gas having been used for heating purposes before and that wire gauze has been employed for distributing the heat all of which I disclaim when taken separately or together. But

10 What I do claim as my improvement and desire to secure by Letters Patent is—

The arrangement of the perforated diaphragm g, g , with the air openings 5, 5, and

7, 7, 7, when said diaphragm and air openings are arranged with the gas pipe B, and 15 gauze C, in the bottom of the iron as specified in the foregoing specification and represented in the accompanying drawings, all for the purpose of detaining and equally distributing the heat over the surface of the 20 bottom of the iron as and for purposes mentioned in the foregoing specification.

JAMES GOODIN, JR.
